UNITED STATES PATENT OFFICE

149,237

DESIGN FOR A GOLF TEE OR SIMILAR ARTICLE

John W. Tutt, Glendale, Calif.

Application July 11, 1946, Serial No. 131,515

Term of patent 14 years

(Cl. D34—5)

To all whom it may concern:

Be it known that I, John W. Tutt, a citizen of the United States of America, residing at Glendale, in the county of Los Angeles and State of California, have invented a new, original, and ornamental Design for a Golf Tee, or Similar Article, of which the following is a specification, reference being had to the accompanying drawings, forming a part thereof.

The figure is a perspective view of a golf tee, showing my new design.

I claim:

The ornamental design for a golf tee or similar article, as shown.

JOHN W. TUTT.
